MOTOR CONTROLLER

James M. Naul, Fanwood, N. J., assignor to The Singer Manufacturing Company, Elizabeth, N. J., a corporation of New Jersey

Application December 8, 1942, Serial No. 468,248

10 Claims. (Cl. 201—51)

This invention relates to manually operable controllers for electric sewing machines, and has for one of its objects the provision of a simplified and improved controller of the carbon disk compression type which has a gradual variation in resistance over a wide range of movement of the manually controlled actuator.

Another object of this invention is to provide a carbon compression rheostat of the pile-type, in which the carbon disks are compressed by means of a flat spring, the effective length of which is decreased proportionally to the pressure applied to the carbon pile.

Another object of the invention is to provide improved means for closing the electric circuit through the carbon pile, and short circuiting the carbon pile when the actuator has reached the point at which the maximum pressure has been applied to the pile.

With the above and other objects in view as will hereinafter appear, the invention comprises the devices, combinations and arrangements of parts hereinafter set forth and illustrated in the accompanying drawing of a preferred embodiment of the invention, from which the several features of the invention and the advantages attained thereby will be readily understood by those skilled in the art.

In the drawing:

Fig. 1 is a longitudinal vertical section through the controller casing, showing the controller operating mechanism, and the base of the controller in elevation.

Fig. 2 is a top plan view of the base of the controller with the controller unit and its operating mechanism mounted thereon.

Fig. 3 is a side elevation, showing the side opposite that shown in Fig. 1.

In the embodiment selected for illustration, my improved controller is housed in a casing comprising a hollow top or cover member 10 and a base plate member 11, each of which is preferably molded from synthetic resin, such as "Bakelite." Secured on the top-face of the base 11 by means of the U-shaped sheet metal strap 12 and screws 13 extending through the base plate 11, is a carbon compression rheostat comprising a tubular porcelain body 14 housing a stack 15 of carbon disks.

Pivotedly secured by the pivot bolt 16 to a lip 17 struck up from the metal strap 12 is a bell-crank lever 18 having one of its ends 19 bent in the form of a U. Between the limbs of the U there is secured by the pin 20 a contact roller 21.

To the other limb of the lever 18 there is pivotally secured at 22 one end of a link 23, the other end of which is pivotally connected at 24, to a three arm lever 25, fulcrumed at 26, on the ears 27, of a plate 28, fixed to the base 11.

The cover 10 is formed with a rectangular opening or guideway 29, in which is fitted a manually operable push button or pedal 30, bifurcated at its lower end to receive the ends of a cross-bar 31 carried by the operating arm of the lever 25. The above described pedal and pivotally arranged lever 25 are old and well known and are more fully disclosed in the patent to Schenk, No. 2,117,257, dated May 10, 1938.

15 A flat spring 34 has one of its ends secured to one limb of an L-shaped member 33 fixed to the base 11 by the screws 33'. The central portion of the spring engages the conducting pressure head 35 of the rheostat and the other end 20 of the spring 34 is formed with an offset portion 36 which rests against the upstanding limb of an L-shaped stop 31, fixed to the base 11 by a screw 38. It will be understood that the stop 37 is arranged so that the spring 34 contacts or bears 25 very lightly on the conducting pressure head 35 except when engaged by the roller 21.

To maintain the bell-crank lever 18 in the position shown in full lines in Fig. 2 a sheet metal L-shaped member 40 is fixed to the base 11 by the screws 41, and hooked to the upstanding limb of the member 40 in one end of a tension spring 42. The other end of the spring 42 is hooked in a slot 43 in a tongue 44 formed on the lever 18. The spring thus holds the lever 18 in its normal or off position, this position being fixed by a shoulder 25' on the lever 25 which shoulder engages the plate 28 as illustrated in Fig. 3, when the lever 18 reaches off position.

40 Fixed to the base 11 by the screw 45 is a plate 46 having an upstanding lip 47 formed with a laterally extending portion 48 the purpose of which will be hereinafter explained. For the purpose of adjusting the initial pressure on the 45 carbon pile a screw C is threaded into the base of the tubular body 14 and passes through the base into engagement with the bottom of the carbon pile. By this arrangement the initial pressure 50 may be adjusted to control the initial pressure of the spring 34 on the carbon pile. A lock nut 50 is provided for the purpose of locking the screw in its adjusted position. The position of the tubular body 14 may also be adjusted by loosening the screws 13 and sliding the body 14 55 to the desired position.

Operation

When the push button or pedal 30 is pressed downwardly the three-arm lever 25 is swung about its pivot 26. The movement of the lever 25, through the link 23, is communicated to the lever 18 thereby causing the lever 18 to swing about its pivot 16. It will be noted in Fig. 2 that when the lever is in the position shown in full lines, the contact roller 21 does not engage the spring 34. The initial movement of the lever 18 causes the roller 21 to engage the spring 34 and the circuit is thereby closed through the carbon pile resistor.

The circuit at this time is as follows: from the lead A to the plate 46, from the plate 45 through the lead B to a screw C which extends into the porcelain body 14 and into engagement with the carbon stack therein. Through the carbon stack to the conducting pressure head 35, thence through spring 34, roller 21, lever 18, spring 42, the member 40 and thence through the lead D.

It will be understood that continued downward movement of the pedal 30 causes the lever 18 to swing further about its pivot and moves the roller 21 along the spring. As the lever 18 and roller 21 approach the position shown in dotted lines in Fig. 2 the pressure on the carbon pile is increased thereby reducing the electrical resistance offered by the carbon disk resistor. When the lever 18 finally reaches the position shown in dotted lines, it engages the laterally extending portion 48 of the plate 46 and the carbon pile is short circuited. When this occurs the circuit is as follows: from the plate 46 to the lever 18, thence through the spring 42 to the plate 40 and the other side of the line.

From the above it will be observed that when the spring is first engaged by the roller 21, circuit through the carbon pile is established and at this time the effective length of the spring is at its maximum, thus a very light pressure is exerted on the carbon pile, and therefore, the resistance offered by the carbon disk pile is at its maximum. Further movement of the roller along the spring decreases the effective length of the spring and the pressure on the carbon pile gradually increases until finally the roller is directly over the pressure head 35 at which time the spring is no longer effective and the pressure on the carbon pile is at its maximum and the resistance offered by the pile is at its minimum.

From the foregoing description considered in connection with the accompanying drawings, the construction, manner of operation and several advantages of my improved carbon disk controller will be clearly and fully understood. It is apparent that such a controller has a wide variety of uses and it will be understood that the form, construction and arrangement of the elements employed are susceptible of material variation. Therefore, the privilege is reserved of resorting to all such legitimate changes therein as may be fairly embodied within the spirit of the accompanying claims.

Having thus set forth the nature of the invention, what I claim herein is:

1. A controller for electric motors comprising a base, a carbon pile resistor carried by said base, a flat spring having one of its ends fixed to said base and adapted to exert a pressure on said carbon pile resistor and a pivoted arm having means thereon for engaging the free end of the spring for the purpose of placing a tension there-

on, and manual means for swinging said arm about its pivot to increase or decrease the pressure applied to the carbon pile.

2. A controller for electric motors, comprising a base, a carbon pile resistor carried thereby, a flat spring adapted to contact one end of the carbon pile resistor, means for securing said spring to said base, and a manually controlled pivoted arm adapted to engage and travel along said spring toward the point of contact between the spring and the resistor for the purpose of varying the pressure applied to the carbon pile resistor.

3. A carbon disk controller, comprising a carbon disk resistor, a flat spring arranged to engage said resistor between its ends, said spring having one of its ends fixed, and a pivotally mounted lever for flexing the other end of the spring, said lever having one end movable along said spring to its point of contact with the resistor.

4. A carbon disk controller, comprising in combination, a carbon disk resistor, a flat contact spring arranged at one of the resistor to apply pressure thereto, said spring having one of its ends fixed relative to said resistor, a manually controlled pivoted lever, and means carried by said lever for flexing said spring when the lever is swung about its pivot to vary the pressure of the spring on said resistor.

5. A carbon disk controller, comprising in combination, a carbon disk resistor, a flat contact spring arranged at one end of the resistor to apply pressure thereto, said spring having one of its ends fixed relative to said resistor, a lever carrying an element at one of its ends for engagement with said spring, said lever being mounted on a pivot so that the end carrying the engaging element moves towards and away from said resistor and manually controlled means for actuating said lever.

6. A carbon disk controller, comprising in combination, a base, a carbon pile resistor secured to said base, a flat spring having one of its ends fixed to said base, said spring being arranged to engage and apply pressure to the resistor at a point intermediate the ends of the spring, a bell-crank lever pivotally secured at the junction of its arms to said base, a member carried by one of the arms of the lever for engagement with the other end of the spring, spring means tending to maintain said lever out of contact with the spring and manually controlled means connected to the other arm of the lever for shifting said lever about its pivot to cause said member to engage the spring and to apply a gradually increasing pressure to said resistor.

7. A carbon disk controller, comprising in combination, a base, a carbon pile resistor secured to said base, a flat spring having one of its ends fixed to said base, said spring being arranged to engage and apply pressure to the resistor at a point intermediate the ends of the spring, a lever pivotally secured to said base for movement about a pivot arranged at right angles to the length of the spring, a contact member carried on one end of said lever and adapted to engage said flat spring and move along the length of said spring to the point of engagement of the spring and the resistor for the purpose of flexing said spring and thereby vary the pressure on the carbon pile resistor and manual means for controlling the position of said lever.

8. A carbon disk controller, comprising in combination, a base, a carbon pile resistor secured

to said base, a flat spring having one of its ends fixed to said base, said spring being arranged to engage and apply pressure to the resistor at a point intermediate the ends of the spring, a lever pivotally secured to said base for movement about a pivot arranged at right angles to the length of the spring, a contact member carried on one end of said lever and adapted to engage said flat spring and move along the length of said spring to the point of engagement of the spring and the resistor for the purpose of flexing said spring and thereby vary the pressure on the carbon pile resistor, means for moving said lever to cause it to engage said spring and connect said resistor in circuit and means effective when said lever reaches a predetermined position for removing the resistor from the circuit.

9. A rheostatic controller comprising, in combination, a base, a tubular shaped carbon disk resistor secured to said base, a lever pivoted at a point intermediate the ends of said resistor, a flat spring contacting one end of the resistor and adapted to apply pressure to the resistor upon being flexed and thereby obtain a variation in resistance offered to the flow of an electric current therethrough, a contact element carried by

said lever and adapted to contact and flex said spring, spring means tending to maintain said element out of contact with the spring and manually controlled means for moving said lever about its pivot the initial movement of which causes the element to engage the spring and a circuit to be established through said spring and resistor.

10. A rheostatic controller comprising, in combination, a base, a tubular shaped carbon disk resistor secured to said base, a lever pivoted at a point intermediate the ends of said resistor, a flat spring contacting one end of the resistor and adapted to apply pressure to the resistor upon being flexed and thereby obtain a variation in resistance offered to the flow of an electric current therethrough, a contact element carried by said lever and adapted to contact and flex said spring, spring means tending to maintain said element out of contact with the spring, a second lever pivoted to said base for movement about a pivot arranged at right angles to the pivot of the first mentioned lever, a link connecting said levers, and a manually controlled sliding member for actuating said last mentioned lever.
